UNITED STATES PATENT OFFICE

1,985,163

MACHINE FOR PACKAGING MATTRESSES
AND THE LIKE

Samuel L. Ginsberg, Jamaica Plain, Mass.

Application February 1, 1932, Serial No. 590,226

6 Claims. (Cl. 226—18)

This invention relates to the packaging or wrapping of bulky articles and while the invention is adapted for use in packaging or wrapping a great variety of different articles which are of a bulky nature, I have, for purposes of illustration, shown and described the invention as it might be used in the packaging of mattresses.

In mattress-manufacturing establishments it is more or less common to wrap the individual mattresses in a paper wrapping before they are shipped, and the operation of wrapping a mattress as now usually carried out requires the services of two or more operatives and takes considerable time.

One of the objects of my present invention is to provide a novel device for packaging and wrapping bulky articles, such as mattresses, by means of which the packaging of any individual mattresses can be easily accomplished by a single individual and in a relatively short time.

In carrying out my invention I propose to use a container, such for instance as a paper bag, of the proper size for packaging mattresses and the invention relates particularly to a novel machine or device by which the container may be opened and held open while the mattress is inserted thereinto.

A further object of the invention is to provide a device of this type which is constructed so that the tying up of the filled containers may be facilitated.

Further objects of the invention are to provide various novel features relating to the packaging of mattresses and other bulky objects which will be more fully hereinafter set forth.

In the drawings wherein a selected embodiment of the invention has been shown the container is illustrated as in the form of a paper bag and will hereinafter be so described but I wish to state that it is not necessary that the container should be a bag as the invention may be embodied in devices adapted to use containers of other types for packaging the bulky articles.

Fig. 1 is a perspective view of an apparatus embodying my invention showing the bag opened ready to receive the mattress;

Fig. 2 is a view illustrating the operation of inserting a mattress into the opened bag;

Fig. 3 is a perspective view showing the apparatus with the mattress packaged and tied;

Fig. 4 is a fragmentary sectional view through one of the supporting brackets for the bag-opening member;

Fig. 5 is a fragmentary sectional view through one of the bag-opening members and showing

the manner in which the bag is retained thereon while the mattress is being inserted.

In the drawings 1 indicates a mattress which is to be packaged or wrapped, and in accordance with this invention I propose to wrap the mattress by inserting it into a bag 2 of paper or other suitable material which is made of the right size to receive the mattress. The bag is preferably made so that the mattress may be inserted edgewise into the open mouth thereof.

The device herein shown comprises a table for supporting the unfilled bag, and means for opening the mouth of the bag and holding the mouth open while the mattress is introduced into the bag.

The table on which the bag is supported is indicated generally at 3 and it is illustrated as mounted on legs or standards which are preferably adjustable as to their length so that the table may be placed at any desired height.

Any approved means may be employed for varying the length of the legs. As herein shown these legs comprise the front legs 4 and the rear legs 5. Each front leg 4 comprises the two telescopic sections 6 and 7, the upper sections 7 being connected to the under side of the table and telescoping into the lower sections 6.

8 indicates pins adapted to extend through any one of a plurality of holes in the upper sections 7, said pins thereby holding the legs extended to the desired length.

The table is of a size to receive the bag 2 and as stated above this bag is constructed so that the mattress 1 can be inserted edgewise through the open mouth of the bag.

To facilitate the insertion of the mattress into the bag I have provided bag-opening means which may be manually manipulated to open the mouth of the bag and to hold the mouth open while the mattress is being inserted as shown in Figs. 1 and 2. The bag-opening means herein shown comprises two bag-opening plates or members 11 which are mounted on the front edge of the table and are capable of being moved toward and from each other and also are capable of being swung about a vertical axis.

Each bag-opening member is carried by a post 12 which is pivotally mounted in a supporting bracket 9, each post being held in any adjusted position by means of a set screw 10. The bracket supports 9 are located at the front edge of the table 3 and each is formed with a flat base portion 13 which bears against the front edge of the table. Located at the front of the table is a bracket-adjusting rod 14 which is rotatably

mounted in suitable bearings 15 secured to the table. This rod 14 is provided with screw-threaded portions 16 which extend through and have screw-threaded engagement with the bracket members 9. The screw-threaded portions at opposite ends of the rods are of opposite pitch, that at one end being a right-handed thread and that at the other end being a left-handed thread. The brackets 9 are thus mounted on the rod 14 but by turning the rod these brackets will be adjusted toward and from each other and during such adjusting movement the base plates 13 will have bearing against the front face of the table 3. The rod may be provided with means for turning it such as the handles 17.

The bag-opening members 11 will preferably have a vertical dimension slightly greater than the thickness of the mattress.

In using the device a bag 2 is placed on the table 3 with the open end adjacent the front of the table where the bag-opening members are mounted. These members will then be adjusted toward each other sufficiently to permit them to be entered into the bag and the bag 2 and said members 11 will be relatively adjusted so as to introduce the members into the bag with the members extending at substantially right angles to the front edge of the table or at right angles to the open mouth of the bag. The rod 14 is then turned in a direction to separate the bag-opening members 11 from each other and the engagement of these members with the edges of the bag will hold the bag open and also hold the edges of the bag taut as shown in Fig. 1.

Since the vertical dimension of the bag-opening members 11 is slightly greater than the thickness of the mattress the width of the open mouth 18 of the bag will be such as to freely permit the mattress to be introduced edgewise into the bag.

The outer face of each bag-opening member 11 is preferably formed with a spur 19 which grips or punctures the bag and thus holds it from slipping off from the bag-opening members while the mattress is being inserted.

When the bag has been opened the operative can readily take a mattress and introduce it edgewise into the bag. In handling a mattress it is convenient for the operative to carry the mattress on his shoulders and partly extended arms and by having the table at the proper height the operative can carry the mattress in this way to the table and easily introduce it into the open bag.

20 indicates a back stop which is shown as removably carried by the table near its rear end and which serves to prevent the bag and mattress from slipping off from the table.

This stop is shown as provided with legs 21 adapted to be inserted into apertures formed in the table 3. When the mattress 1 has been introduced into the bag the shaft 14 is operated to move the bag-opening members toward each other and the set screws 10 may then be backed off to allow the bag-opening members to be swung into a position such as shown in Fig. 3 in which position they are entirely removed from the bag. The bag may then be closed by folding the open end in some appropriate way. Subsequently the closed bag will preferably be tied with suitable ties, such for instance as tapes, strings, straps, wire, etc. To facilitate this operation the table is formed with a plurality of grooves 22 in which proper lengths of ties 23 may be placed before the bag is placed on the table.

After the mattress has been introduced into

the bag and the mouth end of the bag has been folded to close the bag then the ends of the ties which are in the grooves 22 may be brought up over the top of the bag and tied thereby fastening the package.

The extensibility of the front legs 4 permits the front of the table to be placed at the most convenient height for the particular operator using it.

The two front legs 4 are shown as connected by cross members 24 and the rear legs 5 are also connected by other cross members 25. These legs are supported by base members 26 having brackets 27 to which the legs are secured.

While I have herein illustrated the invention as applied to the packaging of mattresses yet I wish to state that the invention is not limited to the packaging of mattresses but may be adapted for use in packaging other bulky articles.

I claim:

1. In an apparatus for packaging mattresses and the like, the combination with a table for supporting a container to receive the mattress, which table is provided with grooves to receive tie members for tying up the package, of container-opening members carried by the table and adapted to turn about a vertical axis to permit them to swing into and out of the mouth of a container supported on said table, manually-operated means for separating the container-opening members from each other after they have been swung into the mouth of the container and for retaining them in their adjusted positions, thereby to hold the mouth open.

2. In an apparatus for packaging mattresses, the combination with a table for supporting a mattress-receiving bag, of bag-opening members carried by the table and movable bodily towards and from each other, each bag-opening member adapted to turn about a vertical axis, which turning movement causes them to enter the mouth of a bag supported on said table, and means operable independently from the operation of inserting a mattress into the bag to move said members away from each other after they have entered the bag and to hold them in adjusted position, thereby holding the mouth of the bag open and taut.

3. An apparatus for packaging mattresses and the like comprising a table for supporting a bag to receive the mattress, two brackets carried by the table at the front edge thereof, a bag-opening plate movably supported by each bracket, said plates by their movement being adapted to enter the mouth of a container supported by said table, and an operating screw connected to the brackets by which they may be separated from each other thereby causing the plates to hold the mouth of the bag open.

4. An apparatus for packaging mattresses and the like comprising a table for supporting a bag to receive the mattress, two brackets carried by the table at the front edge thereof, a bag-opening plate movably supported by each bracket, said plates by their movement being adapted to enter the mouth of a container supported by said table, and an operating screw connected to the brackets by which they may be separated from each other thereby causing the plates to hold the mouth of the bag open, each plate having a spur on its outer face to puncture the bag thereby to prevent the bag from being pulled off from the plates during the introduction of the mattress thereinto.

5. An apparatus for packaging mattresses comprising a table to support a bag adapted to receive the mattress, two brackets supported by the

table at the front edge thereof, a bag-opening plate pivotally mounted on each bracket, said plates by their pivotal movement being adapted to enter the mouth of a bag supported by the table, and 5 means for moving the brackets positively away from each other thereby to cause the plates to hold the mouth of the bag open while the mattress is introduced thereinto.

6. An apparatus for packaging mattresses and 10 the like comprising a table for supporting a bag to receive the mattress, two brackets carried by

the table at the front edge thereof, a bag-opening plate movably supported by each bracket, said plates by their movement being adapted to enter the mouth of a container supported by said table, and an operating screw connected to the brackets by which they may be separated from each other thereby causing the plates to hold the mouth of the bag open, said table having grooves therein to receive tie members by which the package may be tied.
